UNITED STATES PATENT OFFICE.

WILLIAM C. TREGONING, OF CLEVELAND HEIGHTS, OHIO.

SEPARABLE ELECTRICAL CONNECTION.

Application filed January 16, 1923. Serial No. 613,063.

This invention relates to improvements in a separable electrical connection, and method of making the same. While certain of the structure illustrated as embodying the invention is particularly adapted for a separable attachment plug, it is to be understood that the invention is equally applicable to so-called convenience outlets in the walls or base-boards of buildings, as well as to connections with various pieces of electrical apparatus, wherein fixed connection blades are secured to the base of the structure and an element with blade recesses on the live end of a flexible cable is engaged therover. The invention contemplates the production of an electrical connection having a minimum number of fastening elements and the contact members of which are so anchored in the body that they will be maintained in operative position under all conditions of severe usage.

Electrical connections, and more especially separable plugs, as heretofore constructed, have in many instances involved a large number of parts which, while holding the several elements of the assembled plug in rigid position, involve an extensive operation in assembling. Likewise in the separable plugs and like connections in common use, it is very difficult to seat the contact blades in the contact recesses because of the difficulty in bringing the ends of the blades into register with the openings of said recesses.

It is the object of the invention to simplify the structure of the separable plug to the point where it may be manufactured with the minimum waste of material and the maximum of strength, as well as to permit the several elements making up the device to be assembled in complete form with a small amount of labor. It is also an object of the invention to provide a plug or similar connection with guide means whereby the ends of the blades may be directed into position to register with the contact recesses and thus permit the coacting parts to be assembled largely through the sense of touch. Other objects of the invention will appear in the course of the following description. To the accomplishment of the foregoing and related ends, said invention, then, consists of the means hereinafter fully described and particularly pointed out in the claims.

The annexed drawing and the following description set forth in detail certain structure embodying the invention and method of making the same, such disclosed means and method constituting, however, but several of various forms in which the principle of the invention may be used.

In said annexed drawing:—

Fig. 1 is a central longitudinal sectional view of a separable attachment plug embodying the invention; Fig. 2 is an end view of the cap section of the plug; Fig. 3 is a view partially in section, showing one of the blades embedded in the cap section; Fig. 4 is a perspective view of one of the blades before insertion in the cap section; Fig. 5 is a sectional view of the inner end of the base section; Fig. 6 is an end view of the inner end of the base section; Fig. 7 is a perspective view of the outer end of the cap section showing the guide grooves; Fig. 8 is an end view of the inner end of a modified form of the base section; Figs. 9 and 10 are detailed views in perspective showing the modified contact elements used with the device shown in Fig. 8; Fig. 11 is a view showing a plate for a wall or base board having the guide grooves and other features of the base section of the electrical connection; and Fig. 12 is a central longitudinal sectional view of a separable attachment plug of the modified form shown in Figs. 8, 9 and 10.

While various other embodiments of the invention are within the scope of the claims, one of the most complete forms thereof is incorporated in the separable plug type of connection.

The plug in its preferred form comprises a base section 1, and a cap section 2, adapted to be separably associated. The base section has a body 3, of non-conductive material, such as bakelite, having a substantially cylindrical form and having screw threads 4 integrally formed about its circumference adjacent one end, adapted to be engaged by a screwthreaded section 5 formed upon the standard contact shell 6, which is adapted to be firmly secured to the end of said base section, and which constitutes the means of engaging said plug in the usual electric socket terminal (not shown). The base section just referred to is provided with a flattened outer face 7, having a pair of helical, or inclined, segmental grooves 8 formed

therein at a point mid-way between the center and the circumference of said face. Each of said grooves is preferably of somewhat less than semi-circular extent and one end of each of said grooves merges with the flat face of said plug, and is preferably beveled on its outer side and widened at its outer end. Each groove is provided on its inner side with a straight wall 9, while the other end of said groove is within the body of the plug at a point in alignment with the opening of one of the blade contact recesses formed longitudinally of the plug and hereinafter described in detail. In this manner, when the ends of the blades upon the cap member of the plug are placed against the upper face of the base member of said plug, and rotated, they will ride upon the inclined or beveled portions of the grooves and be centered when brought into contact with the straight inner sides thereof. Upon being further rotated said blade ends will strike the end wall or abutment 10 provided in alignment with one side of each of the respective blade contact recesses, and be thus brought into registry with said recesses. The blades may then be forced downwardly into tight engagement with the contact members in said recesses. Centrally of the end of the plug, opposite the flat face just described, a central projection 11 is provided, having flattened sides 12 meeting with angularly disposed seats or ledges 13 against which contact leaves are adapted to bear. These contact leaves 14, 15, are adapted to be positioned in recesses 16, 17, extending longitudinally through the base member of the plug, the ends of the recesses upon the flat face of the base member intersecting one end of each of the respective helical grooves and the other ends of said recesses defining the outer margins of the ledges or seats at either side of the central projection. Said ledges are formed at a slight distance below the end surface 18 of the main portion of the base section, and notches 19, in alignment with said ledges, are formed outwardly of said blade contact recesses.

The contact members for the blades in the preferred form of the separable plug, are formed simply of ribbon strips 21, 22, of bronze or other suitable metallic elements, and are bent at their lower ends to form blade contact springs 23, 24. They are provided adjacent their upper ends with shoulders 25, 26, to engage the ledges upon the body of the plug and are angularly disposed in such manner as to be adapted to be held firmly clamped in position upon said ledges by means of the flange 31 of the screw-threaded contact shell heretofore referred to when the same is in position upon the threaded end of the plug. The upper end of one of said contact members is formed as an outwardly extending spring arm 27 and is engaged beneath the flange of the shell to make electrical connection therewith. The upper end of the other contact member is bent so as to conform to the rectangular outline of the central extension 70 upon said plug and form the central contact member 28 thereof. The shoulder 25, provided upon said last-mentioned contact member, is held in position upon the ledge or seat 13 by means of the flange 31 of said shell 6 after a small block 32 of insulating material has been inserted above said shoulder. In this manner, the shell will be insulated from the strip of metal forming the central contact member and will be brought 80 into firm contact with the end of the other strip of metal for which the shell itself is the contact terminal when screwed into an electrical socket terminal of standard form.

In order to prevent the shell from shifting its position when screwed upon the base member, a pair of notches or depressions 33 are formed in the body of said base member at either side of the central extension 90 of said base member at points intermediate of the socket apertures, and the flange of said shell is depressed into said notches by any suitable means.

In Figs. 8, 9, and 10, is illustrated a modified form of base member and contact elements, the principal difference between said member and the form heretofore described comprising the provision of a pair of lateral ears 41, 42, upon each of the metal contact members 43, 44, for the blades, and corresponding lateral notches or seats 45, 46, at the sides of the recesses 47 for said blade contacts, against which seats said ears are adapted to engage.

As is shown in Figs. 9 and 10 of the drawing, the contact members 43 and 44 in the modified form of the base member, differ in certain respects from those in the preferred form of base member. Thus, the contact member 43 which conveys the electrical current from the shell is not bent upon itself to form the spring contact arm 48, but said arm is bent directly outwardly toward the shell; and the contact member 44, instead of being bent to form a shoulder against which a block of insulating material is seated, has a tongue 49 struck outwardly against which the insulating block bears when said block is pressed downwardly by the flange of the shell.

The cap section of the plug is adapted to be used with either form of base member heretofore described and is of the standard form with a central aperture 50 for the flexible conductor cable. The blade members 51 are formed from sheet metal by cutting out a series of angle bars nested, one within the other, and thus occasioning practically no wastage of material. The angle bars so produced are wiped into cylindrical 13

form at one end to provide a sleeve 52 which is then screw-threaded to receive the binding screws of the standard type. Excepting for the formation of said screw sockets, the 5 metal for the blades lies in a single plane. No sharp angles occur as the sleeve or cylindrical portion involves merely the rolling of the metal strip and not its being displaced laterally. However, in addition to 10 the holding effect to be obtained by embedding the blades in the insulating material forming the cap member of the plug, it has been found desirable to provide a tongue or lateral extension 53 adjacent the apex of said 15 angle bars, so disposed as to lie within the body of the block at approximately an angle of 45 degrees to the plane of the blades. In this manner, an anchorage of great effectiveness is provided for each of said blades. 20 The exterior finish of the detachable section of the plug is preferably that shown in Fig. 1 wherein a knurled edge 54 is formed extending over a large area adjacent the upper circumference of said section. In 25 this way ample gripping surface is provided for rotating the cap member of the plug with the blades pressed upon the top face of the lower section until they strike the guide grooves and are brought into register 30 with the blade sockets in the manner heretofore described.

The manufacturing of the top section of the plug is carried on in a suitable molding apparatus, pins being inserted in the screw 35 sleeves until after the hardening of the insulating material about the base of the blade sections.

It will also be noted that at the inner angle of each of the blade sections a fillet 55 is provided, such fillet not only serving as 40 a strengthening means for the blade, but also as a guide for the conductor cable ends, in conformity with the safety requirements in force in many places. Thus the conductor cable end rides against the inclined 45 face of the fillet as the binding screw is tightened, and seats properly beneath the head of said screw. Without such fillet the cable end could swing away from the binding post and short circuit through contact 50 with the other cable end or blade section.

At the upper end of each of the blades a depression or recess 61 is provided on the outer side, said depression having straight 55 side walls and a bottom substantially V-shaped in longitudinal section. These depressions are adapted to be engaged by pressed up dome-like projections or lugs 62 formed at appropriate positions along the 60 inner sides of the blade contact members.

As is clearly shown in Fig. 11, the base member may be in the form of a wall plate 63, the guide grooves functioning in the 65 same manner as where the other type of base member is employed. When the connection

is to be applied to an electric iron or some similar article, it is desirable to have the blades mounted directly upon said article and the guide slots and contacts in the cap section in order that danger of shock may be avoided through handling a cap section with "live" blades.

Other modes of applying the principle of my invention may be employed instead of the one explained, change being made as regards the structure or method herein disclosed, provided the means stated by any of the following claims or the equivalent of such stated means be employed.

I therefore particularly point out and distinctly claim as my invention:—

1. In an article of the character described, the combination of a cap section having a pair of contact blades and a base section, said base section having a pair of longitudinal 85 blade contact recesses, seats formed adjacent said recesses, contact elements in said recesses having angular portions adjacent thereto for engagement with said seats, and a contact shell provided with a straight inwardly extending flange at its upper edge parallel to the angular portions of said contact elements for pressing the same firmly against said seats.

2. A separable attachment plug base member having a pair of longitudinal blade contact recesses, a projection formed at the outer end of said base member between said recesses, a contact element positioned in one of said recesses and extending over the end of said central projection, a shoulder on said contact element, a second contact element seated within the other recess, a shoulder formed on said second contact member, a screw-threaded section formed upon the body of said base member, and a flanged contact shell adapted to be engaged upon said screw-threaded section of said base member to coact with said shoulders to hold said contact members in operative position.

3. A separable attachment plug base member having a pair of longitudinal blade contact recesses, contact elements in said recesses, a projection formed at the outer end of said base member between said recesses, a pair of seats formed in said base member adjacent said respective recesses, a contact element positioned in one of said recesses and extending over the end of said central projection, a shoulder on said contact element for engagement with one of said seats, an insulated block seated over said shoulder, a second contact element positioned within the other blade recess, a shoulder formed on said contact member for engagement with the other of said seats, a free resilient end; provided on said second contact member, a screw-threaded section formed upon the body of said base member, and a flanged contact shell adapted to be engaged upon said

screw-threaded section of said base member to coact with said shoulders to hold said contact members in operative position.

4. A separable attachment plug base member having a pair of longitudinal contact recesses, contact elements in said recesses, and downwardly and inwardly inclined faces adjacent said recesses on one side for guiding

the ends of the blades into alinement with said blade recesses, and upstanding vertical walls adjacent said recesses on the opposite sides, to prevent movement of said blades past said recesses.

Signed by me, this 11th day of January, 1928.

WILLIAM C. TREGONING.
